INVENTOR.

UNITED STATES PATENT OFFICE.

WILLIAM C. BOWLEN, OF PROVIDENCE, RHODE ISLAND, ASSIGNOR TO THE WIGHTMAN AND HOUGH COMPANY, A CORPORATION OF RHODE ISLAND.

DESIGN FOR A BROOCH OR SIMILAR ARTICLE.

SPECIFICATION forming part of Design No. 86,152, dated December 9, 1902.

Application filed October 28, 1902. Serial No. 129,178. Term of patent 3½ years.

To all whom it may concern:

Be it known that I, WILLIAM C. BOWLEN, a citizen of the United States, residing at Providence, in the county of Providence and State of Rhode Island, have invented and produced a certain new, original, and ornamental Design for a Brooch or Similar Article, of which the following is a specification.

Figure 1 is a face view of my new design embodied in a brooch, and Fig. 2 a side elevation of the same.

As shown in the drawings, the leading or material feature of my design consists in a circular body outline A, extending forward some distance from the frame ornamentation B. A plain curved bead *a* ornaments the face of the former. In detail the frame portion comprises at intervals throughout its circuit the representation of a floweret *b*, spring-

ing from the body portion. Intermediate the flowerets and completing the wreath or frame are scroll ornaments *c*. The center of the body portion is circular and unornamented within the marginal bead *a*.

My design is obviously applicable to articles similar to brooches.

Having described my invention, what I claim as new, and desire to secure by Letters Patent, is—

The ornamental design for a brooch or similar article, as herein shown and described.

In testimony whereof I have affixed my signature in presence of two witnesses.

WILLIAM C. BOWLEN.

Witnesses:

HORATIO E. BELLOWES,
EBENEZER CALLAHAN.
